(57) **CLAIM**

The ornamental design for a round mixing bowl, as shown and described.

DESCRIPTION

FIG. 1 is a perspective view of a round mixing bowl showing our new design;

FIG. 2 is a front view thereof;

FIG. 3 is a right side view thereof;

FIG. 4 is a left side view thereof;

FIG. 5 is a back view thereof;

FIG. 6 is the top view thereof; and,

FIG. 7 is the bottom view thereof.
